UNITED STATES PATENT OFFICE.

DE WITT TAYLOR LYON, OF CHICAGO, ILLINOIS, ASSIGNOR OF ONE-HALF TO BABET
R. H. LYON, OF CHICAGO, ILLINOIS.

RADIATOR.

Application filed August 1, 1925. Serial No. 47,579.

My invention relates to improvements in radiators, and it consists in the combinations, constructions, and arrangements herein described and claimed.

5 An object of my invention is to provide a radiator in which the headers are made very shallow for permitting the air to freely pass by the headers without obstructing the flow of air.

10 A further object of my invention is to provide a radiator of the character described in which the headers themselves act as heat radiator means, and to this end the headers are provided with curved heat radiator 15 fins, these fins causing the air to take a circuitous path as the air passes through the radiator, thus more effectually heating the air.

A further object of my invention is to 20 provide a radiator of the character described in which the pipes of the radiator carry heat radiator fins, these fins also being curved so as to function in the same manner as the fins projecting from the headers. The fins 25 of the headers and the fins carried by the pipes are arranged for causing the air to flow through these fins regardless of the position of the radiator, that is, the radiator will function whether it is standing up or 30 lying down on any one of its sides.

A further object of my invention is to provide a radiator of the character described in which the inlet and the outlet openings are identical to permit either of these openings 35 to act as an inlet or an outlet opening. Furthermore, these openings are disposed in such a position with respect to the radiator that they will provide an outlet opening for the radiator that is always disposed at 40 the lowermost point in the radiator regardless of the position of the radiator.

Other objects and advantages will appear in the following specification, and the novel features of the invention will be particularly pointed out in the appended claims.

45 My invention is illustrated in the accompanying drawings, forming part of this application, in which—

Figure 1 is a diagrammatic sectional plan view showing a number of the radiator sections coupled together, these sections being housed in a casing for providing a heating unit.

50 Figure 2 is a side elevation of one of the sections,

Figure 3 is a plan view of Figure 2, and Figure 4 is an end elevation of Figure 2. In carrying out my invention I provide a radiator section consisting of an upper header 1 and a lower header 2. It will be 60 noted at this point that the headers 1 and 2 are very shallow. The headers are constructed this way so as to permit air to be readily forced past the headers without having the headers offer undue resistance to the 65 air. Of course the headers have a large enough water capacity to feed the pipes 3 that connect the headers together.

The upper surface of the header 1 and the lower surface of the header 2 are provided with arcuate-shaped fins 4. These fins in the present form of the device are integral with the headers and provide arcuate-shaped passageways through which the air is forced. When the headers are in 75 their upright position, the fins on the header 2 support the radiator section. In addition to the fins 4, I provide a plurality of fins 5. These fins are disposed between the headers 1 and 2 and have openings for receiving 80 the pipes 3. The fins are arcuate in shape so as to provide arcuate passageways for the air, and in the present form of the device, are soldered to the pipes. It is obvious that the fins 5 may be secured to the pipes 3 in 85 any other well known manner.

In Figure 3, I show the inlet and outlet openings of the section. These openings are disposed at opposite corners of the radiator section so as to have either of the 90 openings act as a drain for the section no matter in what position the section may be disposed. In this way all of the condensed steam is led away from the radiator section.

From the foregoing description of the 95 various parts of the device, the operation thereof may be readily understood. In Figure 1, I show a number of radiator sections connected together so as to provide a radiator unit. In this figure the sections are vertically disposed and the inlet openings 10 are connected to a steam inlet pipe 6, while the outlet openings 11 are connected to a drain pipe 7. The sections are disposed in a casing 8, the casing in turn carries a fan 105 9 which may be operated by any means so as to force the air through the casing and past the radiator sections.

One of the principal objects of the invention is to provide a radiator section which 110

may be disposed in any position desired, and which will afford a perfect drain for the condensed steam no matter in what position it is disposed, and which will also cause the air to take a circuitous path between the fins no matter in what position the radiator may be. A further object is to provide headers that are very shallow so as to offer very little resistance to the air. The fins 4 are curved so as to add a large amount of heating surface to the headers. These fins cause the air passing across the headers to follow a zigzag path. The air is split up into innumerable currents which are deflected and reflected by the heating surface as these currents pass by the radiator sections. In like manner, the fins 5 split up the air into a number of small currents and cause these currents to take a zigzag path through the radiator. The fins 5 greatly enlarge the heating area of the radiator.

The inlet and outlet openings are designed so that either of the pipe connections may be used for either the supply or return connections, and when either of these pipe connections is used for the return connection, it makes no difference whether the radiators are set vertically, horizontally, or laid flat on their sides. In any of these cases, there will always be a perfect drainage for the condensation or return water, because the low point of these pipe connections 10 and 11 is always below the low point of the pipes 3 making up the radiator proper.

The sections are complete in themselves and require no connections of any kind between each other, except the steam inlet and the water outlet pipes. After the proper number of radiators are set up to form a bank of the proper size, and after these radiators are in proper relationship to each other, the band is complete and is ready for the steam fitter to make the proper supply and return connections to the various radiator sections, which make up the bank. After the steam fitter has made his connections, the sheet metal worker can enclose the entire bank with the sheet metal casing

8 and connect this casing to the fan 9, as shown in Figure 1.

I claim:

1. A radiator comprising a pair of headers, pipes connecting said headers, one of said headers having an opening near one end and one side at the outer surface of the header, and the other header having a similar opening near the opposite end and the opposite side and at its outer surface, whereby one of said openings will be substantially at the highest point of the radiator, and the other at the lowest point in any position of the radiator.

2. A radiator comprising a pair of headers, pipes connecting said headers, one of said headers having an opening near one end and one side at the outer surface of the header, and the other header having a similar opening near the opposite end and the opposite side and at its outer surface, whereby one of said openings will be substantially at the highest point of the radiator, and the other at the lowest point in any position of the radiator, and radiating fins projecting from said headers on the outer faces thereof, the outer edges of the fins on each header being in a common plane, whereby the fins on either header may serve as a support for the radiator.

3. A radiator comprising headers of very shallow depth, heat-radiating fins carried by said headers, said fins also being adapted to support the radiator, thereby spacing the headers from the supporting surface, pipes connecting said headers together, and heat-radiating fins carried by said pipes, said first and second named sets of fins being positioned on said radiator for causing the air to take a circuitous path through the radiator, regardless of the position of the radiator, the edges of said fins being arranged to lie in the planes of a rectangular prism, whereby the radiator will be supported by the fins in all of its positions, thus providing passageways for the flow of air through the radiator.

DE WITT TAYLOR LYON.
